UNITED STATES PATENT OFFICE.

ARCHIE P. FAHNESTOCK, OF LONG ISLAND CITY, NEW YORK, ASSIGNOR TO FAHNESTOCK ELECTRIC COMPANY, OF LONG ISLAND CITY, NEW YORK, A CORPORATION OF WEST VIRGINIA.

SPRING TERMINAL CLIP.

Original application filed June 6, 1923, Serial No. 643,715. Divided and this application filed March 27, 1924. Serial No. 702,436.

To all whom it may concern:

Be it known that I, ARCHIE P. FAHNESTOCK, citizen of the United States, residing at Long Island City, in the county of 5 Queens and State of New York, have invented certain new and useful Improvements in Spring Terminal Clips, of which the following is a specification.

The present invention relates to binding 10 posts or fastening devices for the terminals of electrical conductors and consists in the combinations and arrangements of elements hereinafter described and particularly set forth in the accompanying claims.

15 The invention has for its purpose to provide a device of this character wherein the conductor terminal may be readily applied to or removed from the clip through the instrument of the terminal piece alone, i. e., 20 without necessitating the use of the hands or any implement for manipulating the clip as a requisite to applying the terminal piece thereto or for removing the same.

A further purpose resides in providing a 25 terminal clip having these automatic features which will securely hold the conductor in firmly gripped or clamped position, readily permitting the insertion and removal of the conductor and insuring proper 30 electrical contact at all times between the conductor and the fastening device.

The invention is further characterized in 35 that the clip is especially adapted for that type of work wherein a large number of clips are mounted on a terminal block in close proximity to the end that the respective conductors may be applied to position or removed at will, and thereby avoiding the necessity for using both hands, or the implements usually employed for separating 40 the respective clip members to receive the terminal pieces as now required.

This application forms a division of my co-pending application for United States 45 Patent Serial No. 643,715, filed June 6, 1923.

The invention is shown by way of illustration in the accompanying drawings wherein—

50 Figure 1 is a perspective view of the clip;

Figure 2 a top plan view thereof;

Figure 3 a side elevational view;

Figure 4 an end elevational view showing the terminal piece applied; and,

Figure 5 is an end elevational view showing the terminal piece removed. 55

Referring to the construction in further detail and wherein like reference characters designate corresponding parts in the different views, 23 designates the body portion 60 of suitable spring metal slotted for approximately half of its length to provide a tongue member 24 adapted to have limited and free movement between the side portions 25. The ends of said portions 25 are constructed 65 to provide hook members 26, and the tongue 24 is formed with a hook 27 which cooperates therewith to hold the terminal piece to the clip. In applying the terminal piece to this type of clip the tongue 24 is 70 depressed by said terminal piece to bring the hook elements 26 and 27 into alinement when the terminal piece may be moved into position.

It is to be understood that I do not desire 75 to limit myself to the precise details of construction and arrangement herein set forth, as it is obvious that various modifications may be made therein without departing from the essential features of the invention. 80

Having thus described my invention, what I claim as new is—

A fastening device for electrical conductors comprising a substantially flat and bifurcated member, and a resilient tongue, 85 said bifurcated portion having a pair of hook elements, and the resilient tongue having a hook element located between and in off-set relation to said pair of hook elements, said resilient tongue adapted to be engaged by the conductor for applying said conductor to the device, and said hooked elements constructed to secure the conductor. 90

95 In testimony whereof I affix my signature.

ARCHIE P. FAHNESTOCK.
